UNITED STATES PATENT OFFICE.

CRANDALL W. ROSECRANS, OF LUNDA, OHIO.

STOCK-CHUTE.

No. 890,180.

Specification of Letters Patent.

Patented June 9, 1908.

Application filed June 26, 1907. Serial No. 380,931.

To all whom it may concern:

Be it known that I, CRANDALL W. ROSECRANS, a citizen of the United States, residing at Lunda, in the county of Union and State of Ohio, have invented a new and useful Stock-Chute, of which the following is a specification.

This invention has relation to stock chutes and it consists in the novel construction and arrangement of its parts as hereinafter shown and described.

The object of the invention is to provide a chute of simple and durable construction which may be easily and readily converted from a lower deck loader to an upper deck loader and vice versa for double-deck stock cars.

The chute consists primarily of a runway in which is located a hinged inclined bottom. The runway is also provided with a fixed bottom upon which is mounted studs to support the edges of the hinged bottom when the same is swung down over the fixed bottom. The side of the runway to which the upper bottom is hinged is provided with an upright upon which is mounted a pivoted catch which is adapted to engage the edge of the hinged bottom when the same is swung up and hold the said hinged bottom in elevated position. A block is also attached to said upright and a tackle passes around the pulley of said block and is fixed at one end to the hinged bottom in the vicinity of the free edge thereof and is adapted to be wound around and thereby secured to a cleat preferably secured at the end of the runway.

In the accompanying drawing:—Figure 1 is a longitudinal sectional view of the chute. Fig. 2 is a transverse sectional view of the same, and Fig. 3 is a perspective view of the lower corner of the inclined bottom of the chute.

The chute comprises a runway formed of the vertical sides 1 and the fixed bottom 2. The upper edges of the sides 1 are inclined in the usual manner and any suitable passages may be provided for leading the animals to the runway. The bottom 3 is hinged to one of the sides 1 of the runway and when swung down lies in inclined position over the fixed bottom 2 and extends from one side 1 to the other side 1 of the said runway. The free edge of the bottom 3 is supported upon the studs 4 which prevent the said bottom 3 from sagging or vibrating as the animals

pass over the same and thus the animals are not unnecessarily frightened or jostled by being compelled to pass over a rickety floor in ascending to the upper deck of a stock car. The side 1 of the runway to which the bottom 3 is hinged is provided with an upright 5 to which is pivoted a catch 6. Said catch is adapted to engage the free edge of the bottom 3 when the same is swung up and thus hold the said bottom in its upright position. A block 7 is also attached to the upright 5 and the tackle 8 passes around the pulley of the said block 7 and is attached at one end to the bottom 3 in the vicinity of the free edge thereof and is adapted to be wound around a cleat 9 which is located preferably at one end of the runway.

From the foregoing description it is obvious that when a double-deck car is to be loaded the bottom 3 may be swung down when the animals may pass up through the runway upon the said bottom into the upper deck of a car. When the upper deck is filled the bottom 3 is raised by means of the tackle 8 and is held in its raised position by the catch 6 when the animals may pass along the bottom 2 of the runway upon the lower deck of the car. The bottom 3 is also provided with a handle 10 located near its lower end and by means of which the said bottom may be swung up or down by an operator who is inside of the runway.

Having described my invention what I claim as new and desire to secure by Letters-Patent is:—

1. A stock chute comprising a runway having vertical sides and a fixed bottom, an inclined bottom hinged to one of the vertical sides, studs located at the vertical sides of the chute and adapted to support the edges of the hinged bottom and being supported by the fixed bottom.

2. A stock chute comprising a runway having vertical sides and a fixed bottom, an inclined bottom hinged to one of the sides, studs located at the vertical sides of the chute and supported by the fixed bottom and adapted to support the edges of the hinged bottom, an upright attached to the sides to which the hinged bottom is hinged and a catch pivoted upon said upright and adapted to engage the edge of the hinged bottom.

3. A stock chute comprising a runway having vertical sides and a fixed bottom, an inclined bottom hinged to one of the sides, an

upright attached to the side of the runway to which the inclined bottom is attached, a block attached to said upright, a tackle passing through said block and being attached to 5 the inclined bottom in the vicinity of the free edge thereof, a cleat attached to the chute, a catch mounted upon the upright and adapted to engage the free edge of the hinged bottom and studs located at the vertical sides of 10 the chute and supported by the fixed bottom

and adapted to support the edges of the hinged bottom.

In testimony that I claim the foregoing as my own, I have hereto affixed my signature in the presence of two witnesses.

CRANDALL W. ROSECRANS.
